[57] CLAIM

The ornamental design for an aerial chair, as shown and described.

DESCRIPTION

FIG. 1 is front elevational view of the aerial chair;
FIG. 2 is a rear elevational view of the aerial chair;
FIG. 3 is a right, perspective view of the aerial chair;
FIG. 4 is a left, perspective view of the aerial chair;
FIG. 5 is a right-rear, perspective view of the aerial chair;
FIG. 6 is a left-rear, perspective view of the aerial chair;
FIG. 7 is a top, plan view of the aerial chair; and,
FIG. 8 is a bottom plan view of the aerial chair.
Black dots at the juncture of cords in all figures are intended to represent knots.

Fragmentary criss-cross shading showing in all views is understood to represent a fabric material and is repeated throughout the surfaces shown.

The broken lines in FIGS. 1, 3, 4, and 7 represent conventional stitching.
